VENTED CLOSURE

Daniel H. Bierman, Malverne, N. Y.

Application July 12, 1945, Serial No. 604,706

2 Claims. (Cl. 220—44)

1

This invention relates to tanks or tank installations and to means associated therewith for use in ascertaining the condition of the tank in respect to the quantity of liquid therein.

In certain tank installations, for example fuel oil below-deck supply tank installations in ships, dry docks, etc., the tank is disposed at a low level and is provided with a filling pipe which extends to a higher level, a venting pipe which extends from the tank to a proper level, and a fitting comprising a tube extending into the tank through which a liquid-depth measuring device such as a sounding-measuring rod or a chain carrying a float may be inserted into the tank for ascertaining the depth or quantity of fuel oil therein, the outer end of the tube through which the measuring device is inserted being normally closed in fluid tight fashion by a removable cap. Ordinarily, in tank installations of the character described the outer end of the tube and the cap thereon is disposed at a level substantially lower than that of the upper ends of the filling and vent pipes, for example at the machinery deck of the ship or dry dock. Accordingly, it frequently happens that when the tube sealing cap is removed from the measuring tube oil is forced out of the outer end of the measuring tube, thus resulting in oil wastage and also in splashing of oil on the machinery deck or on the machinery as well as on those in the vicinity and also creating a fire hazard.

The primary object of the present invention, therefore, is to provide means by which it can be readily determined, without removing the sealing cap from the sounding-measuring tube, whether the condition of the tank is such that oil will be forced out of the measuring tube if the sealing cap is removed. In other words, the means provided in accordance with the present invention enables one to readily determine whether the tank is filled or at least partly empty thus obviating the objections and disadvantages hereinbefore referred to and in addition obviating the loss of time and effort required in measuring the contents of a full tank.

Another object of the invention is the provision of a device of simple construction and operation for accomplishing the above mentioned primary object of the invention.

The above and other objects, features and advantages of the present invention will be fully understood from the following description considered in connection with the accompanying illustrative drawings.

In the drawings:

Fig. 1 is a vertically sectional view of a device embodying the present invention;

Fig. 2 is a transverse sectional view on the line 5 2—2 of Fig. 1;

Fig. 3 is a view partly in elevation and partly in section illustrating the operation of the device;

Fig. 4 is a view illustrating more or less diagrammatically a tank installation including the present invention.

Referring now to the drawings in detail, the tank installation comprises, as illustrated in Fig. 4, a fuel oil or other liquid-containing tank T which is disposed at a low level, for example in the lower part of a ship or dry dock. Said tank T is provided with a filling pipe 10 which extends to a higher level L at which it is provided with a removable filling cap 12. A vent pipe 14 with which the tank is provided extends upwardly from the tank to a suitable point normally at a higher level than that of the upper end of the filling pipe 10. The tank is also provided with a sounding tube 16 in which the measuring device (not shown) is positioned or through which the measuring device is inserted for ascertaining the level of the liquid in the tank. The lower end of tube 16 is open whereby said tube is in fluid-flow communication with the interior of the tank. The upper end of said tube terminates at a level substantially below the upper end of the filling pipe. For example, in a ship or dry dock the upper end of the measuring tube 16 may be about 23 feet below the deck or level L at which the upper end of filling pipe 10 is positioned.

In accordance with the present invention, the upper end of said measuring tube 16 is provided with a fitting 18 which includes a removable cap 20 which provides a fluid seal for the upper end 40 of sounding tube 16. It will be understood that when the tank T is filled with air, oil or other liquid air is compressed in the upper part of the sounding tube 16 and that the degree of compression is in proportion to the hydrostatic head 45 of the oil or other liquid in the tank plus the hydrostatic head of the oil or other liquid which may be present in pipes 10 and 14 which, as illustrated in Fig. 4, are shown to have oil therein up to the points 22 and 24, respectively. It will be noted that the sealing cap 20 is at the level 50 of the machinery deck D so that it can be conveniently removed to permit the insertion of the measuring device for ascertaining the quantity of oil or other liquid in the tank. The construction 55 and operation of the fitting 18 whereby to accom-

plish the objects of the present invention will now be described.

The device or fitting 18 embodying the present invention comprises a part here shown as a pipe coupling 26 which is screwed on to the upper end of sounding tube 16 and is internally threaded at its upper end 27. An externally threaded tube or bushing 28 is screwed into the upper end 27 of coupling 26. The upper end 30 of bushing 28 provides a seat for a leather or other suitable gasket or packing 32 carried by the tube-sealing cap 20. Said gasket or tube-sealing part 32 is held against the inner surface of the head 34 of the cap by the cap screw 36 and interposed washer 38. As here shown cap screw 36 is provided with an opening 40 to receive the end connection of a measuring chain (not shown). It will be understood that the opposite or lower end of the chain has a float connected thereto so that when the cap 20 is removed the liquid level may be determined by withdrawing the measuring chain until the slackness therein is eliminated. This type of measuring device is well known and as it does not in itself constitute a part of the present invention, illustration or further description thereof is unnecessary. It will be understood, however, that the measuring chain can be omitted in which case a measuring rod can be inserted into the measuring tube 16, when cap 20 is removed, for ascertaining the level of the liquid in the tank.

In accordance with the present invention the peripheral skirt 42 of cap 20 is provided with one or more, here shown as a plurality of, relief passages 44 which extend downwardly therein from points adjacent to and below the outer marginal edge portion of packing 32 to the lower end of the skirt. Each relief passage 44 is disposed outwardly of the internally screw threaded surface 45 of the skirt. The upper or inner end of each relief passage is in fluid-flow communication with the interior of cap 20 but is disposed outwardly of the tube-sealing part of gasket 32 so that said inner end of the passages is out of communication with tube 28 when the cap 20 is in its fully closed or tube-sealing position and so that said inner end of the passage is placed in fluid-flow communication with tube 28 when said cap is slightly unscrewed or retracted to a position in which it is out of complete tube-sealing engagement on tube 28. It will be understood that if the cap 20 is unscrewed sufficiently to break the fluid seal provided between gasket 32 and upper edge 30 of tube or bushing 28, when the tank T is filled or substantially filled, fluid will flow through the relief passages 44. More specifically, when the cap 20 is turned slightly on tube 28 to start the unscrewing thereof from said tube and the tank T is filled or substantially filled, a warning of such condition of the tank will be given first by release of air from the upper part of sounding tube 16 through passages 44 followed substantially immediately by the flow of oil or other liquid through said passages as illustrated in Fig. 3. It will be noted, by reference to Fig. 3, that the small quantity of oil thus allowed to escape from the tank is directed downwardly and is thus prevented from flowing upwardly on to the operator of the device or on to the deck D. Preferably, as here shown, the device of the present invention is provided with a splash cup 46 which is secured on the upper end

of coupling 26 by a nut 48 threaded on to bushing 28. Splash cup 46 is preferably provided with drain ports 50. The head 34 of cap 20 is provided as here shown with a lug 52 in which an operating bar or handle 54 is secured to facilitate the turning of cap 20.

It will be understood that various changes in the details of construction and in the arrangement of parts may be made in the device of the present invention without departing from the underlying idea or principles thereof within the scope of the appended claims.

Having thus described my invention, what I claim and desire to secure by Letters Patent is:

1. A device of the character described comprising an upright tube and a cap mounted on the top end of said tube for movement thereon from a tube-sealing position to a retracted position, said cap having a top part which engages and seals the tube in the first mentioned position of the cap and having a fluid passage extending downwardly wholly within the cap body from the interior to the exterior of the cap, the inner end of said passage being out of communication with the tube when said cap is in said tube-sealing position and being in communication with said tube when said cap is in said retracted position, and a splash-cup surrounding said tube and positioned below the outer end of said passage to receive the fluid discharged therefrom.

2. A device of the character described, comprising an upright tube having an externally threaded top end, and a cap internally threaded so as to be mountable on the top end of said tube for movement thereon from a tube-sealing position to a retracted position, said cap having a top part which engages and seals the top end of said tube in the first mentioned position of said cap and having a fluid passage extending downwardly wholly within the cap body from the interior to the exterior of the cap, the inner end of said passage being out of communication with the tube when said cap is in said tube-sealing position and being in communication with the top end of said tube when said cap is in said retracted position, and a ring-shaped splash cup surrounding said tube and positioned below the outer end of said passage to receive the fluid discharged therefrom, the inner wall of said ring-shaped splash cup being formed by said tube.

DANIEL H. BIERMAN.
